UNITED STATES PATENT OFFICE

2,404,183

ENCLOSED SWITCH

Edwin W. Landmeier, Erlanger, Ky., assignor to
The Wadsworth Electric Manufacturing Company, Covington, Ky., a corporation of Kentucky

Application August 7, 1943, Serial No. 497,835

6 Claims. (Cl. 200—50)

1

The present invention relates to enclosed switches including the general class wherein the movable contacts are actuated by a pivoted or rotary member and has for an object the provision of a simple sliding actuator operable from the exterior of the cabinet for operating such an enclosed switch.

A further object of the invention is to provide an externally operated slide of the class referred to which is adapted to provide for front-operated switch cabinets as well as side-operated switch cabinets, and which is well adapted to cabinets having an interlock between the switch actuator and the cabinet door or the fuse compartment door, or both of them.

Still another object of the invention is to provide an arrangement of this character that is easily and inexpensively adapted to meet the varying requirements of the customer regarding the interlocking of the switch operation with the switch enclosing cabinet.

It is also an object to provide for any and all of the aforesaid features with a few inexpensive stamped metal parts and at the same time to eliminate to a large degree the necessity of special cabinet construction in meeting the requirements at hand.

These and other objects are attained by the means described herein and disclosed in the accompanying drawings, in which:

Fig. 1 is a plan view of an enclosed switch embodying the invention, partly broken and partly shown in dotted lines.

Fig. 2 is a cross-sectional view taken on line 2—2 of Fig. 1.

Fig. 3 is a cross-sectional view taken on line 3—3 of Fig. 1.

Fig. 4 is a perspective view of the actuator slide forming a detail of the invention.

Fig. 5 is a fragmental cross-sectional view showing the mode of adapting the device of the invention to a side-operated switch box.

Fig. 6 is a plan view showing the arrangement of the actuator of the invention with an interlock on the fuse compartment door.

Fig. 7 is a cross-sectional view taken on line 1—1 of Fig. 6.

Fig. 8 is a cross-sectional view taken on line 8—8 of Fig. 6.

Fig. 9 is a fragmental plan view of the inside of the cabinet door of Fig. 6.

Fig. 10 is a perspective view of the actuator slide of Fig. 6.

Fig. 11 is a plan view of a switch cabinet showing in dotted lines a modified form of inter-

2

lock between the fuse door and the switch actuator slide.

Fig. 12 is a cross-sectional view taken on line 12—12 of Fig. 11.

Fig. 13 is a cross-sectional view taken on line 13—13 of Fig. 12.

Fig. 14 is a cross-sectional view taken on line 14—14 of Fig. 12.

Fig. 15 is a fragmental plan view of the inside 10 of the cabinet door of Fig. 12.

Fig. 16 is a fragmental plan view showing a cabinet in open position and embodying the invention, wherein the actuator slide is carried by a bracket fixed in the cabinet.

Fig. 17 is a cross-sectional view taken on line 17—17 of Fig. 16.

Heretofore a large variety of externally operated enclosed switches has been known and each has entailed special cabinet construction to meet 20 the different customers requirements and to accommodate the selected rotary switch.

By the present invention I have provided a simple means whereby the various kinds of switches including those with rotary operated 25 moving contact assemblies may be actuated by a simple slide which will actuate any of the moving contact assemblies. The rotary type of moving contact mounting is by far the most commonly used in the art so that the present in-

30 vention has a very wide range of adaptability in the art. One of the important advantages of the invention is its easy and inexpensive adaptability in making front-operated enclosed switches using ordinary simple cabinets and practically 35 any make of switch of the commonly used type as aforesaid. Front-operated switches are capable of closely ganged installation and are extremely advantageous in places where space is limited.

40 Reference is now made to Figs. 1, 2, and 3, wherein a switch box 20 of any desired construction has a front opening door 21 hinged thereto. The door is slotted longitudinally for a distance near the latch side at 22 to define the path and 45 the limits of movement of a suitable external handle or knob 23, the shank member 24 of which extends through said slot 22 and is secured to an actuator slide plate 25 which is freely slidable on the inside face of door 21 between a pair of guide 50 flanges 26 which are suitably fixed on the inside face of the door.

For convenience of assembly the shank 24 may 55 comprise a bushing 241 with a screw 27 countersunk in the handle and passing through the bushing, and threadedly engaged in a perforation 28

in the actuator slide 25. Rigidly fixed to the slide 25 is a depending member 29 having an aperture or slot 30 which receives an angularly disposed pin 31 of a crank arm 32 whereby the rotary moving contact assembly of a switch 33 is operated. The switch illustrated by way of example is of the construction shown in my United States Patent Number 2,255,669 of September 9, 1941, but the invention herein is not to be considered as limited in any respects to the particular switch.

The switch 33 is secured within the box in any suitable manner as, for example, by fastening the switch base to the back wall by screws.

The crank bar 34 is suitably journaled for rotary motion in simple brackets 35 which, in this case, are secured to the back wall of the box by means of screws 36. The crank arm 32 may be removably applied to the crank bar by passing a rectangular portion of the bar, intermediate the journaled mountings, through a correspondingly shaped aperture in the arm. The switch, as shown, is of the quick-break type, the spring 37 which is connected to pin 31 being arranged, in known manner, to become tensioned during the initial movement of the crank arm 32 to quickly complete the movement of the latter after it passes over dead-center. As will be well understood by those versed in the art, any suitable quick make and quick break mechanism may be interposed between member 29 of the slide and the crank arm 32, or if desired the crank arm may be completely subject to manual operation through the slide.

From the foregoing description it will be understood that the moving contacts 38, carried by the arms 39 will assume the position shown in Fig. 2 when the slide 25 is in the position shown in full lines, and that when said slide is moved longitudinally until the handle 23 assumes the dotted line position shown, said contacts will each complete an electrical circuit through a pair of fixed contacts 40-41 (see also Fig. 1).

An interlock between the switch actuating mechanism and the door 21 is inexpensively provided by fixing an angle piece 42 to the latch-side wall of the cabinet 20 so located that, when slide 25 is in the upper or "on" position, an offset lug or flange 43 on the slide will assume a position directly beneath the projecting lug or flange 44 of the angle piece 42 and thus prevent opening of door 21 until the slide is moved to its opposite limit of movement and the switch has assumed an "off" position, (see Fig. 1). Once the door has been opened while the switch is in a safe ("off") condition, it is of course possible to again close the switch in order to make routine meter tests and inspections. A suitable door latch 45 is provided.

In Fig. 5 the invention is shown adapted to a side-operated switch actuator, the parts being only slightly modified and reversed in their respective mountings. That is to say the guide flanges 260 are mounted on opposite sides of a slot 220 in the sidewall 200 of the box and the slide 250, reciprocable therein by a handle 230, has fixed thereto a member 45 with spaced apart lugs 290 and 430. The lug 290 is slotted (like member 29 of Fig. 4) and receives the crank arm 320. The lug 430 moves along the inner face of the switch box door 210 when the latter is closed, and assumes a position above the lug 440 on said door when the slide 250 is in switch closing position.

Reference is now made to Figs. 6-10 inclusive, which are illustrative of one form of the invention with an interlock with a fuse door mounted

on the cabinet door to preclude opening of the fuse door while the switch is closed. Under these conditions the cabinet door is customarily sealed in any suitable manner so that the customer may have access to the fuses but not to the remainder of the interior of the cabinet.

This form of the invention involves no major change of structure or function over the device of Fig. 1 in the means for effecting operation of the switch from the face of the switch box door.

The slide 2500 has an extended rib 46 with a slot 47 to receive the pin 31 in crank arm 32 of the switch 33 to operate the switch as the slide is reciprocated by the handle 48 on the outer face of the slotted cover 49.

The cabinet cover 49 has an opening 50 controlled by a hingedly mounted fuse door 51 which provides access to fuse compartment 52 within the box. This fuse door has on its inner face a spaced away lug 53 forming a way into which a flange 54 on rib 46 of the slide enters when the slide is in switch closing position thereby preventing opening of the fuse door without first moving the switch to an "off" position. A suitable snap latch 55 having a ring handle 56 on the outside of fuse door 51 serves to hold the fuse door closed and a resilient latch lug 57 fastened on the sidewall of the switch box and operating through a slot in the switch box door 49 holds the latter closed. A second interlock to prevent movement of slide 2500 from an "off" position to an "on" position when the fuse door is open is optionally provided, by pivotally mounting an L-shaped latch member 58 on the inside face of cover 49 with an end extending across the top of fuse door opening 50. An inclined faced lug 59 on the fuse door 51 is so mounted that during the final closing movement of door 51, the lug 59 engages the arm 60 of L-shaped latch member 58 near the end of the arm and moves said latch member 58 about its pivotal mounting to thereby withdraw the latch finger end 61 from its seat in a notch 62 in slide 2500 against the yielding pressure of a spring 63. The latch 58 thus holds the slide 2500 in its "off" position while the fuse door is open but is automatically released by the act of closing the fuse door. It will also be remembered that the fuse door is latched against opening when the slide is in the "on" position.

In Figs. 11-15 there is shown a modified form of interlock controlled by the front-operated switch actuator slide. In this embodiment the switch box cover 64 has a fuse door opening 65 therein, controlled by a hinged fuse door 66. This door has on its rear face a keeper 67 located just below the top edge to receive the lower edge 68 of a T-shaped bar 69 which is pivoted at 70 on the switch box cover. Bar 69 is biased by spring 71 to urge the edge 68 into keeper 67. The actuator slide 72 is reciprocable in the manner previously described, and has its lower end 73 arranged to depress the adjacent top edge of bar 69 for rocking it on its pivot and thus lifting the edge 68 out of keeper 67 to permit opening of the fuse door by its latch and ring structure indicated generally at 74. (See Figs. 11 and 15). The interlock between the actuator slide 72 and the fuse door 66 comprises a latch member 75 pivoted intermediate its ends on a pin or stud 76 and having a coil spring 77 surrounding the stud and suitably attached to the latch and cover respectively to bias the latch for rotating movement on its pivot in an anti-clockwise direction as viewed in Fig. 15. The upper part of the latch member is notched

at 78 to receive a lug 79 on actuator 72 when the latter is moved to an "off" position and the fuse door 66 is opened. If the fuse door remains closed, however, or is subsequently closed, an inclined lug 83 on said fuse door holds the latch member 75 out of engagement with said lug 79 so that the actuator may be reciprocated when the fuse door is closed. The actuator slide 72 has an apertured or slotted member or yoke 81 to operate the selected rotary or pivoted crank arm of a switch, for example, it may engage the crank pin 31 on a crank 32 of a switch 33 similar to those heretofore described and illustrated.

In the modified structure exemplified in Figs. 16 and 17 the actuator slide 32 is reciprocably mounted in guides 83 which are secured to the bottom face of a slotted flange 84 of a bracket 85. This bracket is rigidly secured to the sidewall 86 of a switch cabinet 87 so that the upper face of flange 84 is immediately beneath the inside of the cabinet cover 88 when the latter is closed (see Fig. 17). The actuating handle or knob 89 is fixed to the actuator slide in any approved manner, for example as hereinbefore described, and operates in the slot 99 of bracket 84 at all times. The cover 88 has a slot 91 with an enlargement 92 at the lower end thereof, which end defines the "off" position limit of movement of the actuator slide. The enlargement 92 is capable of passing over the knob or handle 89 when the slide is in the "off" position. This permits opening and closing of the cabinet cover when the switch is in the "off" position. In all other positions of the slide, the closed cabinet cover is incapable of being opened. The slotted member or yoke 93 on the slide imparts rocking movement to the moving contact crank 32 by engaging the pin or stud 31 thereof in the previously described manner. In this embodiment, as in all others the particular kind of switch employed is entirely a matter of choice. The size and shape of the handle or knob for the slide will be governed largely by the size of the switch structure and by choice of design as in all of the previously described embodiments and in addition to this the enlargement 92 will of necessity be of a size and shape that will pass over the selected knob or handle.

The term rotary switch as used herein includes any switch structure having a moving contact assembly which is actuated by a rotary or pivoted member.

What is claimed is:

1. In an enclosed externally operated switch the combination of a switch cabinet including a movable door, a rotary switch mounted therein, an actuator slide member guidedly mounted on the door of the switch cabinet, a yoke element having an open ended slot on one side of the slide for removably engaging and operating the switch, and a handle piece fixed to and projecting from the other side of the slide, said cabinet door having a rectilinear slot defining the limits of movement of said slide member at the off and on positions of the switch and permitting disposition of the handle on the exterior of the box and said yoke in the interior of the box when the door is closed.

2. An enclosed switch comprising a cabinet, a switch therein including a rotary member rockable about an axis for actuating the switch, a slide reciprocably mounted for movement paral-

lel with a wall of the cabinet, said wall having a rectilinear slot therein which is closed by said slide at all times, a yoke fixed on the slide and having a slot for engaging the rotary member for rocking the same as the slide is moved, a handle stud rigidly mounted on the slide projecting through the slot and defining the limits of movement of the slide at the off and on positions of the switch.

- 10 3. An enclosed switch comprising a cabinet, a switch in the cabinet including a rockable operating member, guides fixed interiorly of the cabinet alongside said switch operating member, a slide having rectilinear movement in the guides, 15 a yoke fixed on the slide for removably connecting said operating member and said slide whereby the operating member is rocked in opposite directions by the slide, the cabinet having a rectilinear slot closed by said slide and adapted 20 to define the limits of movement of the slide, and a handle stud fixed in the slide and extending through the slot for cooperation therewith in limiting the movement of said slide.
4. An enclosed switch comprising a cabinet 25 having a rectilinear slot therein, a switch mounted in the cabinet and including a rotatably mounted member rockable about an axis between limits for opening and closing said switch, a slide reciprocably mounted over said slot within 30 the cabinet adjacent said member, a crank pin on said member, a yoke fixed to the slide and loosely embracing the crank pin, and a manually operable stud fixed on the slide and extending accessibly through the slot for cooperation 35 therewith in limiting manual reciprocation of the slide at the off and on positions of the switch.

5. An enclosed switch comprising a cabinet 40 having a door with a rectilinear slot adjacent the latch side thereof, a rotary switch mounted in the cabinet and having a rockable member disposed wholly within the cabinet for operating the switch, a crank pin in said member, a slide reciprocably mounted on the inside face of the 45 door over the slot in the door, a handle stud accessible from the outside of the door and fixed in the slide through said slot and positively limiting the manual reciprocation of the slide at the off and on positions of the switch, a yoke fixed 50 on the slide and having an open ended slot for receiving the crank pin therein during the closing of the door when the switch is in "off" position, an offset lug on the slide, and a flange member fixed to the cabinet and lying in a plane intermediate the inside face of the cabinet door and the offset lug, said flange being located in a position such that it is superposed over the offset lug when the slide is moved to switch closing 55 position.

6. In a front operated enclosed switch the combination of a cabinet including a hinged door, a slide reciprocably mounted in a plane parallel to and adjacent said door in its closed position, the door having a slot longitudinally of the slide, a handle slidably on the outer face of the door and fixed to the slide through the slot in the door, a rotary switch mounted in the cabinet and means on the slide and switch effecting actuation of the switch as the slide is reciprocated by the exteriorly disposed handle.

EDWIN W. LANDMEIER.
